US00D584705S

(12) **United States Design Patent**
Shimamoto

(10) **Patent No.:** US D584,705 S
(45) **Date of Patent:** ** Jan. 13, 2009

(54) **TELEVISION SET**

(75) Inventor: **Yasutaka Shimamoto**, Tochigi-ken (JP)

(73) Assignee: **Sharp Kabushiki Kaisha**, Osaka (JP)

(**) Term: **14 Years**

(21) Appl. No.: **29/287,705**

(22) Filed: **Sep. 10, 2007**

(51) **LOC (9) Cl.** 14-03

(52) **U.S. Cl.** D14/126

(58) **Field of Classification Search** D14/125-134,

CLAIM

The ornamental design for an "television set," as shown and described.

DESCRIPTION

FIG. 1 is a perspective view of a television set in accordance with my new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a right side elevation view thereof, the left side elevation being a mirror image thereof.

1 Claim, 5 Drawing Sheets
